Application May 28, 1949, Serial No. 95,910
In France June 10, 1948

10 Claims. (Cl. 332—15)

1

The present invention relates to an amplitude modulating device for electric pulses.

In the pulse modulation technique, one often has to modulate pulses in amplitude, either because this modulation is utilized directly or because said modulation constitutes a convenient stage for the production of other types of modulation, in duration or in position, for instance.

The amplitude pulse modulation device which is the object of the invention, offers, with respect to other known devices, generally utilized, a number of advantages namely: simplicity and economy, linearity of modulation, stability as regards the variations of the supply voltages, the possibility of replacing the modulating electron tube by another one, without the necessity of altering any adjustment, the possibility of transmitting wide modulation bands without any difficulty and of using low values of the low frequency excitation.

Characteristically and according to a feature of the invention applying particularly to a multiplex transmission system, the modulating device comprises the superposition on the control grid of an electron tube of the low frequency modulating voltage and of unblocking pulses, the modulating voltage being applied to the primary of a transformer whose secondary is located between the grid of the electron tube and the point common to a resistance and to a detector which clips the signals from a pulse generator.

According to another characteristic and to an arrangement of the invention applying to very wide modulation bands, a low frequency transformer energizes a relatively low resistance placed in series with the detector.

The invention will be described in detail hereinafter by two embodiments shown by way of nonlimitative examples. The description will be given with reference to the appended drawings wherein: Figure 1 shows a device which can be adapted particularly well to multiplex transmission; Figure 2 shows a modification of the device of Figure 1, designed especially for the transmission of wide frequency bands.

In Figure 1, 1 shows a source of pulses having the desired characteristics for the type of transmission utilized. In the case of a multiplex transmission, for instance, the pulse sources may be taps uniformly distributed on a delay line. Resistance 3 is a resistance sufficiently large with respect to the internal impedance of detector 4 for the peaks of the pulses generated at 1, assumed to be imperfectly rectangular, appearing on the input grid of the electron tube 5 to be well

clipped. The effect of this clipping action is primarily to limit to a predetermined value the amplitude of the pulse voltage as supplied by this generator to the grid of tube 5. It is obvious that this limitation point of control electrode voltage can be made to lie inside the linear portion of the anode current/control electrode voltage characteristic curve of said tube 5. Resistance 6 and condenser 7 give, on the other hand, a biasing voltage of such a value that the electron tube 5 is rendered operative only at the time of occurrence of a pulse 2.

The low frequency modulating voltage is applied between 8 and 9 to the primary of a transformer 10 whose secondary winding is connected across a suitable impedance 11. This transformer is designed so as to offer the least possible amount of stray coupling capacities so as to avoid distortion of the pulse applied to the grid of tube 5. 10 The insertion of this transformer between the grid of 5 and the point common to 3 and 4 prevents the low frequency voltage from reacting on the pulse source, since the impedance of the grid circuit is very high at low frequencies. Thus, 15 one avoids, in the case of a multiplex transmission, the cross-talk due to couplings between the various channels through the medium of the pulse source.

Resistance 12 suitably biases the electron tube during the passage of the pulse 2; it also contributes, if not uncoupled by a condenser, to the improvement of the linearity of modulation. 13 20 14 is the load impedance of the tube. 14 shows an output pulse modulated in amplitude.

In the case of a multiplex transmission, the plates of the modulating tubes, such as 5 are connected together. If the type of modulation ultimately desired in the considered multiplex transmission system is not that of amplitude modulation, it will be sufficient to effect later the change 25 in type of modulation in elements common to all channels.

Figure 2 shows a modification, in accordance with the invention, of the circuit described previously. This modification is of particular interest in case very wide modulation bands have to be transmitted over a single transmission channel.

15 is a generator delivering pulses with a suitable recurrence period and whose duration is large enough with respect to said period, a condition not troublesome for a single transmission channel. Under such conditions, if, for instance, the pulse generator does not transmit a direct current, (a transformer or a resistance-capacity

coupling are sufficient to this effect) the pulses, at the output of 15, have the shape shown in 16, the dotted line 17 representing ground potential. These pulses are applied to the detector 19 through the resistance 18. The low frequency modulating voltage is applied, between 21 and 22, across resistance 20 in series with detector 19. 21 and 22 may be connected to the secondary of a low frequency transformer which, in this set-up, does not need to be especially designed with low stray coupling capacitances.

The resistance 20 must be comparatively low with respect to the resistance 18. The signal on the grid of the electron tube 23 is thus the superposition of the low frequency voltage and of the pulses. Resistance 24 fixes the bias during the passage of one pulse and, further, improves the linearity of modulation. Since the tube 23 is blocked between two pulses, its grid potential remains sufficiently below ground potential. An amplitude modulated pulse 26 is obtained at the terminals of the load impedance 25.

The whole of this device does not comprise any condenser, any especially designed transformer nor any time constant and may, if desired, transmit low frequencies, starting from zero frequency.

The electron tubes, in figures 1 and 2 have been shown as simple triodes. It is obviously understood that, if desired, tubes having more than three electrodes, such as pentodes, for instance, can be utilized.

I claim:

1. In a transmission system for recurrent amplitude modulated electric pulses, an electronic tube having anode and control electrodes, means for applying to a control electrode a modulating voltage and a pulse voltage of the recurrence of the aforesaid pulses, means for applying to said control electrode a biasing voltage of such value as to block the flow of anode current in the absence of the applied pulse voltage, and further circuit means to modify the amplitude of the applied pulses to such a degree that in the absence of modulating voltage the voltage of the control electrode due to peaks of the modified pulses lies within the linear portion of the control electrode voltage-anode current characteristic of the tube.

2. System according to claim 1, wherein the modifying means clips the pulses to an amplitude value still sufficient to unblock said tube.

3. System according to claim 1, wherein the modifying means includes a detector having output circuit connected to said control grid and supplied by said pulse voltage.

4. System according to claim 3, including biasing means for said detector causing it to clip the pulses applied thereto.

5. In a transmission system for recurrent amplitude modulated electric pulses, an electronic tube having an anode and control electrode, means for applying to the control electrode a modulating voltage and a pulse voltage, a detector having output means connected to said control electrode and means applying the pulse voltage to said detector; means for biasing said detector to such a degree that, in the absence of modulating voltage, the voltage of the control electrode due to the peak pulse voltage lies within the linear portion of the control electrode-anode cur-

rent characteristic curve of the tube and means for applying to said control electrode a biasing voltage of such value as to reduce the anode current to zero in the absence of the pulse voltage.

6. In a transmission system for recurrent amplitude modulated electric pulses; an electronic tube having a cathode, control electrode and anode; a generator of recurrent electric pulses, a transformer to the primary winding of which the modulating voltage is applied, a circuit connecting said pulse generator and control electrode and including a resistor and the secondary winding of said transformer connected in series; a detector having one terminal connected to a point between said resistor and said secondary winding and its other terminal to a point of substantially constant potential, means for applying to said control electrode a biasing voltage of such value as to reduce the anode current to zero in the absence of the pulse voltage, the resistance of said resistor being sufficient to limit to a predetermined peak value the amplitude of the pulse voltage applied to the control electrode, the voltage of the control electrode remaining within the linear portion of the control electrode-anode current characteristic curve of the tube during the period of peak pulse voltage.

7. A transmission system according to claim 6, in which the point of constant potential to which the detector terminal is connected, is a terminal of a resistor connected in series in the anode-cathode circuit of the tube.

8. A transmission system according to claim 5, wherein the pulse voltage and the modulating voltage are applied in series to the detector whereby the peak value of the pulse voltage varies linearly with the amplitude of the modulating voltage.

9. In a transmission system for recurrent amplitude modulated electric pulses; an electronic tube having a cathode, control electrode and anode; a pulse voltage generator, a circuit connecting said generator and control electrode; a detector and resistor connected in series, one terminal of said detector being connected to said circuit whereby the peak pulse voltage applied to said control electrode is limited to a predetermined value; the resistance of said resistor being substantially less than the internal resistance of the pulse generator, means for applying the modulating voltage to the terminals of said resistor and means for applying to said control electrode a biasing voltage of such value as to reduce the anode current to zero in the absence of the pulse voltage.

10. In a transmission system according to claim 9, wherein the circuit connecting the pulse generator and control electrode includes a second resistor connected in series, said second resistor having a resistance substantially greater than that of the resistor in series with the detector.
